UNITED STATES PATENT OFFICE

126,110

DESIGN FOR A TEXTILE FABRIC

Benjamin S. Granby, New York, N. Y., assignor to The Schwarzenbach Huber Co., New York, N. Y., a corporation of New Jersey

Application February 1, 1941, Serial No. 98,657

Term of patent 3½ years

To all whom it may concern:

Be it known that I, Benjamin S. Granby, a citizen of the United States, residing in the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

BENJAMIN S. GRANBY.
